UNITED STATES PATENT OFFICE.

PIETRO CALAMITA, OF BROOKLYN, NEW YORK.

PROTECTIVE DEVICE FOR VESSELS.

Application filed July 9, 1927. Serial No. 204,527.

My invention relates to protective means for vessels and refers particularly to means for protecting the hull of a vessel from injury due to a projectile impact.

5 An effective device of the character described must be light in weight, must be of such construction as to prevent the passage of a projectile, must largely absorb the impact of the projectile and must present a 10 minimum of water resistance when the vessel is in motion.

The device of my invention possesses all of the above mentioned, and other desirable 15 properties as will be evident upon a consideration of my specification and its accompanying drawings.

In order to accomplish the desired objects, 20 my device comprises two differently constructed parts, one of which protects the bow and stern of the vessel and the other of which protects the sides of the hull.

A consideration of the contour of a vessel 25 shows that when it is in motion, the force of the water is against the face of the protective means at the bow and stern, while the force of the water is parallel with the face of the protective means at the sides of the vessel.

It is evident, therefore, that the construction 30 of the device must be of such a character as to offer the least possible water resistance at these respective portions of the vessel.

I accomplish this by forming my device of 35 a grate-like construction at the fore and aft portions of the vessel, thus allowing free passage of the water therethrough, and forming the side portions of a conduit-form to allow of the unimpeded passage of the 40 water therethrough.

By making my side portions of a double 45 reversed U-shape instead of a closed conduit, I reduce the amount of metal thus reducing the weight, I reduce the amount of surface friction and I produce a device having a certain amount of spring which will absorb the impact of a projectile to some extent, thus reducing the effect of the blow upon the hull.

The advantages of my device will be evident 50 upon a consideration of my specification and its accompanying drawings.

In the accompanying drawings illustrating 55 one form of the device of my invention, similar parts are designated by similar numerals.

Figure 1 is a diagrammatic side view of a vessel carrying the device of my invention.

Figure 2 is a top view of Figure 1.

Figure 3 is a front view of Figure 1.

Figure 4 is a section through the line 4-4 of Figure 2.

Figure 5 is an enlarged sectional view of the protective grate of my device.

The particular form of the device of my invention shown in the accompanying drawings 65 comprises a plurality of double reversed U-shaped supports 10, each having the stays 11 and 12. These supports are fixedly attached to the opposite sides of the hull 13, preferably by stay-rods 14, 14. The U-shaped supports 10, 10 extend along each side of the hull 13 toward the stem and stern of the vessel, the latter two parts being protected as will be described later. Fixedly attached to the outer faces of the U-shaped 75 supports is a protection plate 15.

The stem and stern of the vessel are protected by a grate composed of two base bars 16, 16 connected by a plurality of spaced 80 grate rods, or bars, 17, 17. This protective grate is attached to the hull of the vessel by means of the angle supports 18, 18 and by means of the U-shaped supports 18, 18, similar to those already described.

It will thus be seen that the entire hull 85 of the vessel for a considerable distance below the water-line carries a protective device and that it offers but a very slight increased water resistance.

When the vessel is in motion, the water 90 passes freely through the forward protection grate which is the same general contour as the bow of the vessel, and then passes along the sides of the hull, meeting with only the face resistance of the U-shaped protective 95 plates and then outwardly through the stern protective grate.

My device, therefore, presents an effective protective means of inconsiderable weight, the impact force of a projectile being largely 100 absorbed by the device due to its shape, and which at the same time offers a minimum of water resistance.

I do not limit myself to the particular size, shape, number, arrangement or material 105 of parts, all of which are shown and described as a means for clearly describing the device of my invention.

What I claim is:—

1. In a protective device, in combination 110

with the hull of a vessel, a plurality of double reversed U-shaped members attached to the sides of said hull, a protective plate carried by said U-shaped members and protective grates carried by the bow and stern of said hull.

2. In a protective device, in combination with the hull of a vessel, a plurality of double reversed U-shaped members attached to the sides of said hull, a protective plate carried by said U-shaped members, a protective grate carried by the bow of said hull and having the general contour of said bow, and a protective grate carried by the stern of said hull and having the general contour of said stern.

3. In a protective device, in combination with the hull of a vessel, a plurality of double reversed U-shaped members attached to the side of said hull, a plurality of brace

supports within each U-shaped member, a protective plate carried by said U-shaped members and protective grates carried by the bow and stern of said hull.

4. In a protective device, in combination with the hull of a vessel, a plurality of double reversed U-shaped members attached to the sides of said hull, a protective plate carried by the U-shaped members upon each side of said hull, a protective grate carried by and spaced from the bow of said hull and a protective grate carried by and spaced from the stern of said hull, the whole forming a protection means spaced from and having the general contour of the entire hull.

Signed at New York city, in the county of New York and State of New York this 6th day of July, 1927.

PIETRO CALAMITA.
